United States Patent Office

Des. 207,738
Patented May 23, 1967

207,738

FOOT MEASURING APPARATUS

Michel H. Saad, ½ Dana Electronic Computer Co.,
E. 108 Jackson Ave., Spokane, Wash. 99207

Filed May 9, 1966, Ser. No. 2,213

Term of patent 14 years

(Cl. D52—6)

FIG 2

FIG. 1 is a perspective view of a foot measuring apparatus embodying the instant design;

FIG. 2 is a top view of the apparatus in FIG. 1;

FIG. 3 is an enlarged side elevational view of the apparatus in FIG. 1;

FIG. 4 is a front view of the apparatus in FIG. 1; and

FIG. 5 is a rear view of the apparatus in FIG. 1.

The undisclosed side of the foot measuring apparatus is a mirror image of the side shown.

I claim:

The ornamental design for a foot measuring apparatus, as shown and described.
